CLAIM

The ornamental design for a tablet case, as shown and described.

DESCRIPTION

FIG. 1 is a top, front and left side perspective view of a tablet case showing my new design;

FIG. 2 is a bottom, rear and right side perspective view thereof;

FIG. 3 is a top, rear and left side perspective view showing the tablet case in a state of use;

FIG. 4 is a top, front and right side perspective view showing the tablet case in the state of use;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof; and,

FIG. 11 is an enlarged view of portion 11 in FIG. 3.

The broken lines showing portions of the tablet case illustrate portions of the article, and form no part of the claimed design. The dot-dash broken lines indicate where the enlargements have been taken, and form no part of the claimed design.
